TOY OIL-PUMPING RIG

George W. Eichelberger, Jr., Houston, Tex.

Application November 26, 1943, Serial No. 511,835

1 Claim. (Cl. 46—39)

This invention relates to a toy oil-pumping rig, and has for one of its objects the production of a toy which will simulate an oil-pumping rig in actual operation and appearance.

A further object of this invention is the production of a toy oil-pumping rig having a rotary water storage tank which is associated with a walking beam and an operating means to operate the walking beam and rotary water storage tank.

Other objects and advantages of the present invention will appear throughout the following specification and claim.

In the drawing:

Figure 1 is a side elevational view of the toy;

Figure 2 is a vertical sectional view taken on line 2—2 of Figure 1;

Figure 3 is an enlarged central vertical sectional view through the rotary water tank and illustrating the supporting bearing therefor;

Figure 4 is a fragmentary side elevational view of the detachable walking beam operating rod.

By referring to the drawing, it will be seen that 10 designates the base or platform upon which the toy is mounted. The base 10 supports a toy oil well derrick 11, and this derrick 11 carries a safety walk and railing 12 near the top thereof. A rotary tank 14 is journaled for horizontal rotation upon a bearing 15 carried by the base 10 and a driving pulley 16 is carried by the top of the tank 14, over which pulley 16 passes a driving belt 17. This belt 17 is driven from a pulley 17^a carried by the drive shaft 18. The drive shaft 18 carries a suitable clutch 19 which may be operated to render the pulley 17^a active, or to render the pulley free. A clutch-operating lever 20 is pivotally mounted on a bracket 21 to facilitate the operation of the clutch 19. The shaft 18 is preferably driven by a spring motor 22, such for instance as the type of motor shown in my previous Patent #1,608,783, issued November 30, 1926. Any preferred type of motor may be used for rotating the shaft 18, as this shaft may be operated by an electric motor or by hand without departing from the spirit of the invention. As shown the spring motor 22 may be wound by a crank 18^a which is carried by one end of the shaft 18, and this crank is mounted exteriorly of the removable housing 23 hereinafter described.

A walking beam 24 is pivotally mounted upon a removable standard 25, the lower end of the standard 25 fitting in the supporting socket 26 carried by the base 10. The outer end of the beam 24 carries a pump rod 27 which works freely in the pulley bearing 28 so that the beam 24 and rod 27 may be easily removed if desired, but

when assembled and operating these parts will give the appearance of a pump rod and walking beam structure. The bearing 28 extends vertically through the tank 14, and carries a suitable leak-proof packing 29 at the bottom of the tank and bearing. The pulley 16 may form a part of the tank 14, or it may be secured thereto in any desired manner. A discharge faucet 30 is carried by the tank 14 and may be opened while the walking beam 24 is in motion, to allow water to flow out from the tank and into a suitable outlet 31 which may drain to a suitable point of disposal.

The beam 24 is connected to an operating rod 33 at its rear end which rod is detachably secured 15 to the crank 34 of the shaft 18 in a conventional manner, such as is illustrated in Figure 4. The beam 24 extends through a vertical slot 35 formed in the front portion of the housing 23 and the crank 18^a also extends through a vertical slot 36 formed in the side of the housing 23. This arrangement will permit the removal of the housing 23 to expose the operating mechanism normally shielded thereby. The walking beam 24 and standard 25 may also be removed thereby converting the toy into a rotary drilling rig with the power unit out in the open. This gives the appearance of a modern drill rig. A horizontal partition 37 is formed near the top of the housing 23, and is spaced below the roof 38 to provide a coin saving bank. One panel 39 thereof is slotted to provide an opening through which coins may be inserted, and this panel 39 is preferably hinged, as illustrated, to permit the contents of the bank compartment 40 to be removed.

35 By carefully noting Figure 3 it will be seen that the rod 27 which is slideable in the upper end of the bearing 28 will brace the bearing at its upper end and tend to prevent tilting movement under the pull of the belt 17 upon the pulley 16. Furthermore, the upper end of the bearing will provide a guide for the rod 27 thereby avoiding an additional brace for the upper end of the bearing 28 and avoiding the necessity of providing an additional guide for the rod 27.

45 If desired, a garden hose H may be secured in any desired manner to the derrick 11, as indicated in dotted lines in Figure 1, so that water from the hose may shoot upwardly through the derrick to give the impression of a gusher. The device may be made in a large size to provide a novel lawn ornament. The size may be varied to suit the type of toy desired, and certain other detail changes may be employed without departing from the spirit of the invention, so long as

these changes fall within the spirit of the appended claim.

Having described the invention, what I claim as new is:

A toy of the class described comprising a base, a derrick carried thereby, a rotary tank simulating a rotary pump, said tank having an outlet, a vertical bearing supporting said tank for horizontal rotation, a pulley, means for driving said

pulley, said bearing extending through the tank and pulley, a walking beam mounted adjacent the tank, and a reciprocating rod simulating a pump rod carried by the beam and vertically slideable in the upper end of said bearing, said rod constituting a brace for the upper end of the bearing, and the upper end of the bearing providing a guide for said reciprocating rod.
